UNITED STATES PATENT OFFICE

JOHN COYLE, OF BALTIMORE, MARYLAND, ASSIGNOR TO CONTINENTAL CAN COMPANY, INC., OF NEW YORK, N. Y., A CORPORATION OF NEW YORK

MACHINE FOR COATING CAN ENDS

Application filed April 11, 1929. Serial No. 354,327.

The invention relates to new and useful improvements in a machine for applying a sealing coating in the channel of an irregular shaped can end.

5 An object of the invention is to provide a coating machine wherein the coating is applied with a nozzle which travels over the channel of an irregular shaped can end while said end remains stationary.

10 A further object of the invention is to provide means for controlling the flow of the coating material from the nozzle.

A still further object of the invention is to provide a coating machine of the above 15 type wherein the means for controlling the flow of the coating from the nozzle is so constructed as to lay a coating of uniform thickness in the channel throughout the entire extent thereof.

20 These and other objects will in part be obvious and will in part be hereinafter more fully disclosed.

In the drawings which show by way of illustration one embodiment of the invention:—

Fig. 1 is a view partly in vertical section and partly in side elevation showing a machine embodying the improvements.

Fig. 2 is a vertical sectional view through 30 a portion of the machine on an enlarged scale.

Fig. 3 is a sectional view on the line 3—3 of Fig. 1.

Fig. 4 is a view partly in plan and partly 35 in section of the supporting and operating device for the nozzle, the nozzle being omitted from this view.

Fig. 5 is a sectional view on the line 5—5 of Fig. 2.

40 Fig. 6 is a plan view of an irregular shaped can end which may be coated by the machine as shown.

Fig. 7 is a detail showing the operating 45 lever for raising and lowering the supporting chuck for the can end.

The invention is directed to a coating machine for coating irregular shaped can ends which are held stationary during the coating thereof. The machine includes a supporting chuck for the can end which is shaped

so as to hold the can end in a predetermined position on the chuck. The chuck is raised and lowered for presenting the can end to the nozzle for coating. The nozzle for applying the coating is supported by a bar 55 which is mounted so as to move the nozzle over the channel in the can end. The path of movement of the nozzle conforms to the outline of the channel and as the nozzle follows around the channel the coating is applied to the channel. The nozzle is above the can end so that the can end is placed with its channel facing upward on its supporting chuck. The nozzle is moved by two devices disposed at the opposite ends of the bar 60 which support the bar and impart movements thereto which conform to the shape of the channel in the can end. This is accomplished by a pattern cam associated with each device, a roller on the bar running in said 65 pattern cam and a propelling means which includes a rotating disc having a radial slot and a block slidably mounted in said slot and engaging a roller on the bar. Thus it is that the rotation of the disc will cause the roller 70 to follow around the pattern cam and thus impart a bodily movement to the bar which in turn causes the nozzle supported thereby to follow the outline of the channel in the can end. Means is provided for regulating 75 the flow of the coating material from the nozzle. This is accomplished by a control plate operating on a lever for opening the valve. The valve is closed by means of a spring. The control plate is raised and lowered by a lever having a roller running on a pattern cam. Thus it is that the flow of the 80 sealing material may be cut off so as to allow the coated end to be removed and an end to be coated to be placed on the chuck. 85

When the chuck is raised into proper position for coating, then the cam through the control lever opens the valve and allows the coating to flow from the nozzle. This control cam may be so proportioned as to partially close the valve during coating for regulating the supply at different points in the coating of the end. The speed of travel of the nozzle is a variable speed, inasmuch as the actuating devices have a shiftable connection 90 100

with the roller on the bar. When the connection moves in toward the center of rotation, the speed of travel is less than when it is moved outward away from the center 5 of rotation. The control cam may be so shaped as to regulate the supply so that with the variable speed of travel of the nozzle a uniform layer of coating may be applied to the can end.

- 10 Referring more in detail to the drawings, the machine in the illustrated embodiment of the invention includes a main frame 1 which is provided with two supporting columns 2 and 3 and a central frame structure 4. 15 Mounted in this central frame structure 4 is a support for a chuck 5 on which the can end 6 is placed for coating. This support for the chuck 5 includes a standard 7 mounted for reciprocation in a suitable bearing in 20 a depending bracket 8 carried by the central frame of the machine. The standard is slotted at 9. Housed in this slot is a spring 10; the spring 10 at its upper end engages a positioning pin 11 fixed to the upper end of the 25 standard. The spring at its lower end surrounds a pin 12 mounted on an abutment bracket 13. The upper end of the standard is secured to the chuck by suitable set screws 14. The spring normally tends to raise the 30 standard.

Connected to the lower end of the standard is a lever 15. This lever is in yoke form and the members of the yoke are secured to a collar 16 by means of pins 17. The lever is 35 freely supported on a shaft 18. This shaft 18 is mounted for oscillation in supporting bearings 19 carried by the main frame. Attached to the shaft 18 is an arm 20. The arm 20 is provided with a segment slot 21 (see Fig. 7). A bolt 22 passing through this slot is threaded into the lever 15, and thus it is that the arm 20 may be set in different angular positions relative to the lever 15 and secured thereto in its set positions. On the 40 end of the arm 20 is a roller 23. This roller 23 runs on a cam 24 carried by a hub 25 mounted on ball bearings 26 carried by the depending bracket 8. The hub 25 is attached 45 to and supports an actuating gear 27. When this gear is rotated the cam 24 will be rotated and this cam is so shaped as to press downwardly on the arm 20 and thus oscillate the shaft 18 and lever 15 so as to move the standard and the chuck 5 downwardly 50 compressing the spring 10. The spring holds the roller 23 pressed against the cam 24 and at the proper time the cam will permit the standard and chuck to be raised.

55 The can end 6 is shown more in detail in Fig. 6 of the drawings. This can end is provided with a central depressed portion 28, a flange 29 at its outer edge and a channel 30 located between this central depressed portion 28 and the flange 29. The can end 65 as shown in the drawings is provided with

straight portions along its sides and straight portions at its opposite ends, while at the corners there are curved portions. It is this channel which is to be supplied with the 70 coating, and when the end is placed on the can body the flange on the can body engages the sealing material in the channel and the flange and edge portion of the can end are rolled with the flange on the can body into a double seam. This is a very well known 75 expedient in joining irregular shaped can ends to can bodies.

The coating is applied to this channel by means of a nozzle 31. The nozzle 31 is mounted in a supporting bar 32. The nozzle 31 includes a supporting structure 33 onto which the nozzle is threaded and the bar 32 is provided with an opening conforming to a sleeve carried by the base structure and the nozzle so that the base structure may be placed on the upper face of the bar with the nozzle projecting through the opening and below the bar. The base structure is provided with a conduit 34 through which the coating material flows from a supply pipe 35. This supply pipe 35 is of a flexible character so that the nozzle may be moved in a path conforming to the shape of the channel in the can end. The supply of the coating from the nozzle is controlled by a needle valve 36 mounted in the supporting structure 33 and controlling the discharge opening of the nozzle from within. This needle valve 36 is connected to a lever 37 pivoted at 38 on a bracket carried by the supporting structure 33. In the outer end of the lever 37 is a rod 39 which is clamped to the lever by means of a clamping bolt 40. A spring 41 bears against the bar 32 at its lower end and encircling the projecting end of this rod 39 bears against the lever and normally raises the outer end of the lever thus depressing the needle valve 36 so as to close the nozzle.

The upper end of the rod 39 carries a shoe 42 which contacts with a control plate 43. 110 The under face of the control plate 43 is a smooth horizontal surface and the shoe slides freely on this surface so that the control plate does not in any way interfere with such movements of the bar 32 as may be necessary to cause the nozzle to follow the channel in the can end. The control plate is mounted on two swinging arms 44, 44 which are pivoted to a supporting bracket 45 mounted at the upper 115 end of standards 46, 46 which in turn are mounted on the central frame structure 4 of the machine. Also carried by the bracket 45 is a lever 47. The lever 47 is pivoted at 48 and is connected by a link 49 to the control plate. As the lever 47 is oscillated the arms 44, 44 will be swung toward and from a vertical position and this will raise and lower the control plate at the same time always holding said control plate in a horizontal position. The lever 47 carries a roller 50 which 120 125 130

bears on a cam 51 fixed to a shaft 52. A spring 53 is connected at one end to the lever 47 and at its other end to a projecting lug carried by the bracket 45. This spring is the 5 means for holding the roller 50 in contact with the cam 51. The cam 51 is rotated by a gear 54 which meshes with a gear 55 carried by a shaft 56. The shaft 56 is rotated by means of a sprocket chain 57 cooperating with 10 a sprocket on the shaft 56. This sprocket chain cooperates also with a sprocket on the main driving shaft 58.

The cam 51 is provided with a concentric portion *a* which is of maximum diameter and 15 when the roller 50 is running on this portion *a* the control plate is raised to its extreme upper position and the valve is closed by the spring 41. This control cam 51 is also provided with concentric portions *b*, *b*, *b* and in- 20 termediate these sections *b* are projections *c* of greater diameter. As the roller passes onto the section *b* the valve will be fully opened through the spring 53 moving the roller so as to swing the lever 47 in the direction to lower 25 the control plate. The lowering of the control plate opens the valve. When the section *c* passes the roller 50 the valve will be partially closed. The nozzle as it follows the channel has a variable speed of travel due 30 to the fact that the roller on the control bar is shifted toward and from the center of rotation of the actuating member. The control cam is so shaped as to control the flow of coating so as to produce a uniform thickness of 35 coating with this variable speed of travel of the nozzle. The nozzle is near its maximum travel when the roller moves off the concentric portion and opens the valve. As the nozzle approaches another position of maximum 40 speed the roller passes over the projection *c* and closes or partially closes the valve. Thus it is that a coating of uniform thickness is formed.

The supporting and control bar 32 for the 45 nozzle is mounted so as to move freely in an endwise direction and also freely laterally on the columns 2 and 3. The mechanisms associated with each column are similar and the description of one will answer for the other. 50 At the upper end of the column there is a head 59 with which is associated a cap plate 60. The bar 32 lies between the cap plate and the head 59. Mounted centrally of the column is a shaft 61. The shaft 61 carries a disc 55 62 which is provided with a slot 63 extending diametrically across the disc. Mounted in this slot 63 is a block 64. A roller 65 is secured to the under face of the bar 32 and engages this block 64. The block is free to 60 slide radially of the disc 62. When the roller 65 is set eccentrically to the axis of the shaft 61 then the bar 32 will be given a lateral movement as the disc 62 rotates. Mounted in the cap plate 60 is a control cam plate 66. Said 65 control cam plate is provided with a control

cam raceway 67. The control cam plate is secured to the cap plate by means of bolts 68, 68. The raceway 67 is shaped so that the outer face thereof conforms to the shape of the channel 30 in the can end, that is, it has rounded corner portions with substantially straight portions in between these rounded corners. 70

Mounted on the bar 32 is a roller 69 which lies in this cam control raceway 67. As the disc 62 is rotated it imparts movement to the bar 32 in a lateral direction and also in an endwise direction and this cam control raceway controls the movements of the bar 32. Inasmuch as there is a control cam at both 75 ends of the bar and an actuating device at both ends of the bar, the bar will have a bodily movement, every point of which moves in a path conforming to the shape of the control cams and also conforming to the shape of the channel in the can end. For different size can ends or for different shape can ends the control cam is, of course, changed and one substituted conforming to the shape of the channel which it is desired to coat. 80

The main shaft 58 carries a bevel gear 70 which meshes with a bevel gear 71 on the shaft 61 in the column 3. This imparts rotation to the shaft 61 therein and in turn rotation to the actuating disc in the head at the upper end of the column 3. On this shaft 61 is a spur gear 72 which meshes with the gear 27. Thus it is that the cam 24 is rotated. The gear 27 also meshes with a spur gear 73 fixed to the lower end of the shaft 61 in the column 2, and thus it is that the shaft 61 is 130 rotated and the actuating disc associated therewith. 85

As the main shaft is rotated the actuating discs at the upper end of the columns will be rotated in timing therewith and the chuck will be raised and lowered permitting an end to be placed thereon which is raised into position to receive the coating from the nozzle. The nozzle is at all times over the channel in the can end and as these control discs rotate the bar 32 will be given a bodily movement so that the nozzle will travel about the channel in the can end supplying the coating thereto. The cam 51 is operated by the main shaft 58 and in timing with the movements of the chuck so that when the chuck is in proper position to be coated the control plate for the valve regulating the supply of coating from the nozzle is lowered so as to open the valve and permit the coating to flow from the nozzle onto the can end. The coating is preferably delivered to the nozzle under air pressure so that there is a free flow of the coating immediately upon the opening of the nozzle. The nozzle will travel about the channel until the end is properly coated after which the valve is closed, the chuck is lowered and the end may be removed. Any suitable means may be provided for placing the ends on the chuck and removing the same

therefrom. It will be noted that the can end is stationary when the coating is applied thereto and, therefore, there is no disturbing centrifugal force acting on the coating as it comes in contact with the end and this enables a very uniform laying of the coating in the channel to be accomplished.

It will be understood from certain aspects of the invention that the control of the valve during coating will not be necessary, in which case the control cam 51 will be shaped so as to merely open the valve in proper timing with the presenting of the end and to close the valve at the end of the coating opération.

It is obvious that the structure for supporting and moving the nozzle, also for holding the can end, may be varied without departing from the spirit of the invention as set forth in the appended claims.

Having fully described my invention, what I claim as new and desire to secure by Letters Patent, is:—

1. A machine for coating irregular shaped can ends comprising a coating nozzle, a can end chuck for presenting a can end to said nozzle for coating and for holding said end stationary during coating, means for supporting said nozzle and for moving the same in a path conforming to the channel in the end to be coated, a control valve for said nozzle, a lever connected to the control valve and moving with the nozzle, a spring bearing on the lever for normally holding the valve closed, a control plate with which said lever makes contact continuously throughout the movements of the valve, and means for shifting the position of the plate for controlling the valve.

2. A machine for coating irregular shaped can ends comprising a coating nozzle, a can end chuck for presenting a can end to said nozzle for coating and for holding said end stationary during coating, means for supporting said nozzle and for moving the same in a path conforming to the channel in the end to be coated, a control valve for said nozzle, a lever connected to said valve and movable with said nozzle, a spring bearing on the lever and normally holding the valve closed, a control plate with which said lever makes contact continuously throughout the movements of said valve, a cam rotated in timing with the movements of the nozzle, a lever cooperating with said cam and connected to said plate for shifting the same for opening and closing the valve.

3. A machine for coating irregular shaped can ends comprising a coating nozzle, a can end chuck for presenting a can end to said nozzle for coating and for holding said end stationary during coating, a supporting bar to which said nozzle is attached, means at the opposite ends of said bar for supporting and moving the same bodily for causing said nozzle to travel in a path conforming to the

channel in the end to be coated, each of said means including a control cam, a roller on the bar engaging said cam, and an actuating device for causing the roller to follow the cam.

4. A machine for coating irregular shaped can ends comprising a coating nozzle, a can end chuck for presenting a can end to said nozzle for coating and for holding said end stationary during coating, a supporting bar to which said nozzle is attached, means at the opposite ends of said bar for supporting and moving the same bodily for causing said nozzle to travel in a path conforming to the channel in the end to be coated, each of said means including a stationary control cam, a roller on the bar adapted to travel in the cam, a disc having a raceway extending diametrically across the same, a shiftable member in the raceway, and a roller on the bar engaging said shiftable member, said disc being disposed relative to the control cam so as to cause said roller to follow the control cam.

5. A machine for coating irregular shaped can ends comprising a coating nozzle, a can end chuck for presenting a can end to said nozzle for coating and for holding said end stationary during coating, a bar for supporting said nozzle, means at opposite ends of the bar for supporting and moving said bar so as to cause the nozzle to travel in a path conforming to the channel in the end to be coated, a control valve for said nozzle, a lever moving with the nozzle and connected to said valve, a spring bearing on the lever and holding the valve closed, a control plate having connection with said lever, and means for shifting said control plate for controlling the valve during the movements of said nozzle.

6. A machine for coating irregular shaped can ends comprising a coating nozzle, a can end chuck for presenting a can end to said nozzle for coating and for holding said end stationary during coating, cam means for raising and lowering said chuck and for holding said chuck raised during coating, means for supporting and moving said nozzle in a path conforming to the channel in the end to be coated, a valve controlling said nozzle, a lever movable with the nozzle and connected to said valve, a spring operating on the lever to hold the valve closed, a control plate contacting with the lever, and means operated in timing with the chuck for shifting said control plate so as to open the valve when the end is properly positioned for coating and so as to close the valve when the end has been coated.

7. A machine for coating irregular shaped can ends comprising a coating nozzle, a can end chuck for presenting a can end to said nozzle for coating and for holding said end stationary during coating, cam actuated means for raising and lowering said chuck and for holding said chuck raised during

- coating, a bar to which said nozzle is attached, means at the opposite ends of said bar for supporting and operating the same for moving said nozzle in a path conforming to the channel in the end to be coated, a control valve for said nozzle, a lever connected to the valve and movable with said nozzle, a spring operating on said lever for closing the valve, a control plate contacting with the lever, a cam for shifting said control plate in timing with the movements of the chuck for opening the valve when the end is positioned for coating and for closing the valve after the end is coated.
8. A machine for coating irregular shaped can ends comprising a coating nozzle, a can end chuck for presenting a can end to said nozzle for coating and for holding said end stationary during coating, means for supporting the nozzle and for moving the same in a path conforming to the channel in the end to be coated and at a variable speed, a control valve for said nozzle, and a control cam for the valve shaped so as to control the flow of the coating from the nozzle so as to produce a uniform thickness of coating on the can end.

In testimony whereof, I affix my signature.
JOHN COYLE.
